RADIATOR SUPPORTING DEVICE

John W. Farley, Cleveland, Ohio

Application July 17, 1935, Serial No. 31,907

4 Claims. (Cl. 248—234)

The invention relates to devices for supporting the radiators of heating systems upon the walls of buildings and it aims to provide an exceptionally simple and inexpensive device of this character, yet one which will be readily useable in connection with different types of radiators, quickly and easily adjustable to position the radiator at the desired height and to truly level the same, and rigid and durable.

10 With the foregoing in view, the invention resides in the novel subject matter hereinafter described and claimed, the description being accomplished by reference to the accompanying drawing.

15 Fig. 1 is a perspective view showing one of the improved radiator supporting devices with the wall bracket and the radiator-engaging bracket plate connected with each other in vertically spaced relation, showing also a device for spacing 20 the lower end of the radiator from the wall.

25 Fig. 2 is a combined vertical section and elevation showing the same wall bracket and radiator-engaging bracket plate connected with each other in close relation, the bracket plate being engaged with the upper portion of a radiator.

Fig. 3 is a view similar to Fig. 2 but illustrating the relation of parts when the bracket plate is to engage the lower end of a radiator.

30 Fig. 4 is a perspective view showing a slightly different radiator-engaging bracket plate.

Fig. 5 is a perspective view showing a slightly different wall bracket.

The wall bracket shown in Figs. 1, 2 and 3 comprises a flat horizontal plate 6 to lie between 35 blocks, bricks or tiles 7 of a wall, said plate having a vertically bent inner end 8 to interlock with one or more of the tiles or the like, said end 8 preferably projecting downwardly. The inner end portion of the plate 6 is downwardly offset 40 and terminates in a horizontal flange 9 having a longitudinal slot 10, and the plate portion 11 which connects said flange 9 with the remainder of the plate is disposed vertically and constitutes an abutment to lie against the inner side of the 45 wall.

In Fig. 5, the wall bracket comprises a horizontal plate 12 having a bent inner end 14 corresponding to the end 8 of the plate 6. This plate 12 terminates at its inner end in a horizontal portion 15 having a longitudinal slot 16, and said plate is provided with vertically bent abutment lugs 17 to lie against the inner side of the wall, said lugs being bent either upwardly or downwardly as desired.

55 In Figs. 1, 2 and 3, a radiator-engaging bracket

plate 18 is provided, said plate being disposed in a vertical plane and having a laterally bent inner end providing a flange 19 to lie against the inner side of the wall. Between its ends, the plate 18 is provided with lateral horizontal lugs 20 having 5 openings 21, said lugs being preferably formed by bending the ends of a metal strip 22 which is riveted, welded or otherwise secured to one side of the bracket plate 18. The upper edge of this plate 18 is formed with a concave seat 23 to engage a section-connecting nipple 24 of a conventional radiator 25, said upper edge being provided with three notches 26 to accommodate the usual section-connecting rod or rods 27 of the radiator 25. Some radiators include one tie rod at each 15 end, some are provided with two, some with three and some with none. Any of these types may be supported with the invention.

In Fig. 4, the bracket plate 18^a is identical with the bracket plate 18, with the exception that its 20 lugs 20^a are integral with the upper and lower edges of the plate. In this view, the reference characters 19^a, 21^a, 23^a and 26^a correspond to the formations above described by use of the reference characters 19, 21, 23 and 26. 25

Either one of the bracket plates 18 or 18^a may be connected with either one of the wall brackets 6 or 12. In Fig. 1, a bolt 28 having nuts 29 and 30 at its ends, passes through the slot 10 and through the openings 21 of the lugs 20, one or 30 both of the nuts being locked in any suitable way. The bolt 28 also passes through an eye 31 on the inner end of a horizontal tie-bolt 32, the outer end of this tie-bolt being provided with radiator-engaging means 33. 35

In Fig. 2, a shorter bolt 34 having a head 35 at its upper end and a nut 36, passes through the slot 10 and the lugs 20 for holding the radiator-engaging bracket in closer relation with the wall bracket than in Fig. 1. 40

In Fig. 3, a much longer bolt 37 passes through the slot 10 and through the lugs 20, the upper end of said bolt being provided with a head 38 and its lower end with a suitably locked nut 39. This construction is used when the radiator is to 45 be supported from its lower end, whereas the relations shown in Figs. 1 and 2 are employed to support it from the upper end. In Fig. 3, with the radiator supported at its lower end, a tie-bolt 32^a identical with the tie-bolt 32 is employed 50 for the upper end of the radiator.

It will be observed that the bracket plate 18 or 18^a is narrow vertically compared with its horizontal length, requiring a minimum of metal. The vertical spacing of the lugs 20 or 20^a, how- 55

ever, prevents canting of the plate 18 or 18^a with respect to the suspending bolt 28, 34 or 37, regardless of the vertical narrowness of said plate, and the laterally bent flange 19 or 19^a prevents the wall-engaging end of said plate from cutting into the wall, which would otherwise occur with a plate having such small vertical width.

In Fig. 1, I have shown a device 40 for spacing the lower end of the radiator from the wall, 10 said spacing device being carried by a suspending strip 41 bolted or riveted at 42 to the bracket 18, and in Fig. 4 the opening 43 denotes the point at which the strip 41 may be attached to the bracket 18^a. The spacing device 40 is preferably 15 in the form of a vertical plate riveted, bolted or welded at 44 to the lower end of the strip 41, the ends of said plate being horizontally split and bent to provide upper and lower lugs 45 and 46 which project in opposite directions, the lugs 20 at one end of the plate being intended to abut the wall and those at the other end to abut the radiator.

It will be seen from the foregoing that a novel device has been provided for attaining the desired ends. Excellent results are to be had with the details disclosed but within the scope of the invention as claimed, variations may be made.

I claim:—

1. In a radiator supporting device, a radiator-engaging bracket plate having a radiator seat at its upper edge, said plate being disposed in a vertical plane and having vertically spaced laterally projecting horizontal lugs between its ends, 30 said lugs having openings to receive a suspending bolt, said bracket plate being relatively narrow vertically compared with its horizontal width and having a laterally bent wall-engaging flange 35

on its inner end disposed in a vertical plane, the vertical spacing of said lugs preventing canting of said bracket plate with respect to the suspending bolt regardless of the vertical narrowness of said plate; said flange preventing the inner end 5 of said plate from cutting into the wall as would otherwise occur due to said vertical narrowness of said plate.

2. In a radiator supporting device, a plate to lie horizontally between wall blocks, tiles or bricks, 10 said plate having a vertically bent outer end to interlock with the wall, said plate being of sufficient length to project inwardly from the wall and having stamped-out lugs at its longitudinal edges disposed in a vertical plane to abut the 15 inner side of the wall, said plate terminating in a horizontal inner end portion elongated in a direction parallel with said vertical plane, said inner end portion having a bolt-receiving slot extending unidirectionally with its length. 20

3. In a radiator-supporting means, a spacer comprising a suspending strip for attachment to a wall bracket, and a plate disposed in a vertical plane and secured against one side of said strip to space the lower end of the radiator from the 25 wall, the ends of said plate being provided with lateral lugs to abut the radiator and wall. 25

4. In a radiator supporting means, a spacer comprising a suspending strip for attachment to a wall bracket, and a plate disposed in a vertical 30 plane and secured against one side of said strip to space the lower end of the radiator from the wall, the ends of said plate being horizontally split and bent in opposite directions above and below the splits to provide lugs to abut the radiator 35 and the wall.

JOHN W. FARLEY.
